UNITED STATES PATENT OFFICE.

HORACE HAYDEN, JR., AND WILLIAM F. Z. DESANT, OF NEW YORK, N. Y.,
ASSIGNORS OF ONE-THIRD TO ALBERT R. GOODING, OF SAME PLACE.

ELECTRICAL RAILWAY-SIGNAL.

SPECIFICATION forming part of Letters Patent No. 398,613, dated February 26, 1889.

Application filed February 8, 1888. Serial No. 263,348. (No model.)

To all whom it may concern:

Be it known that we, HORACE HAYDEN, Jr., and WILLIAM F. Z. DESANT, citizens of the United States, residing at New York, in the county of New York and State of New York, have invented a new and useful Electrical Railroad-Signal, of which the following is a specification.

Our invention relates to improvements in block-signals and other railway-signals, and its object is to provide an automatic signal located in the cab of the engineer, and so arranged as to automatically indicate "danger," in the event that a train preceding has not passed off the section in advance. We accomplish these objects by the mechanism described in the accompanying specification and illustrated in the drawings, but particularly pointed out in the claims which follow this specification.

Prior to our invention it was old in the art to so arrange a system of electrical block-signals that the presence of a train on a preceding section of track was indicated to the engineer on a succeeding train by the ringing of an electrical bell in the cab; but in the system of signals referred to the generator was carried in the cab of the locomotive, while in our construction the batteries or generators are permanently located at the respective ends of the sections of track, as will be disclosed.

Referring to the drawings, Figure 1 is a plan view showing a block-signaling system with two locomotives on succeeding sections of track and main and local batteries at the end of each block. Fig. 2 is a side elevation of a modified form of our block system applied to a single line of rails. Fig. 2 is a detail view of the whistle and detent-releasing apparatus designed to give the alarm or signal. Fig. 3 is a plan view showing the circuits applicable to a switch or draw-bridge. Fig. 4 is a plan view showing the circuits at the way-station, with means for announcing to the engineer on a train that he should stop and additional means for announcing the approach of the train. Fig. 5 is a detail view of one of the switching-magnets which operate the block-circuits.

R R R are the rails, divided into main sections, 1, 2, and 3, as shown in Figs. 1 and 2.

L and L' are two locomotives running on successive block-sections. At the end of each block there is a short section of rail, F 55 F' F², (shown in Fig. 2) electrically insulated at each end from the adjoining rails. In Fig. 1 there are two such short sections of rails between each block-section to meet the requirements of the modified form therein 60 shown. Each of the switch-magnets M M' M² is provided with an armature-lever, A A' A², having an armature on each end and pivoted, as shown, so that it may be tilted in either direction. On the end of these armature-levers are insulating-blocks I I' I².

B B B are the batteries for operating the switch-magnets M M' M², as will be described.

w w are the block-signal circuits, and w' w' are the alarm-circuits. (Seen in Figs. 1 70 and 2.)

s s' s² are metallic springs adapted to bear on either the metallic or insulated faces of the armature-levers A, A', or A².

w³ w³ is a local circuit running from the axle 75 of the rear locomotive drive-wheel to the magnet M³ in the cab, and thence to the axle of the cab-truck, the function of which circuit is to energize the magnet M³.

R' R', Fig. 3, are switch-rails having the 80 usual switch-lever, s w, which is provided with a contact-arm adapted to close the circuit of the battery B³, including the circuit-wires w w.

H, Fig. 4, is a hand-switch located in a way-station and adapted to close the circuit of the battery B⁵ and the wires w² w² at the proper time, as will be described.

D is an alarm-bell operated by the battery B² in a local circuit including the armature-lever A⁴ of magnet M⁴ when the train approaches the station.

We will now describe the operation of the modified form in Fig. 1. Suppose the engines L L' to be in the middle of the sections 2 and 3, as shown. When the engine L reaches the point a', there will be no alarm in the cab, for the reason that the battery B' will be short-circuited through the axles of the locomotive drive-wheel and tender-truck wires w', spring 100

S, and armature-lever A. This will indicate to the engineer that the section in advance is clear. If in the meantime engine L' reaches the point A³, the circuit of battery B' will be closed as follows: From the copper pole through the axle of the locomotive drive-wheel, wire w³, magnet M³, wire w³, and tender-truck wheel and axle back to the negative pole of the battery, the short circuit w'w' being broken by the insulation I' between the armature-lever and spring S'. This energizes magnet M³, Fig. 2^a, and causes its armature A³ to release the weighted lever c, which in turn, through the agency of the link W and valve V, permits the whistle W' to be blown. When the engine L advances to the point a, the main circuit of battery B at station 1 is closed as follows: through the wheel of the locomotive between the wires w w, the lower half of magnet M, and to the succeeding section, 2, through the upper half of magnet M'. This causes the armature-levers A and A' to be tilted to the right and left, respectively, thereby placing the circuits in such conditions as to indicate to the engineer of locomotive L' that locomotive L has passed out of block 2, and at the same time leaving the local circuit of battery B' at station 1 in condition to sound an alarm on the locomotive L' when it reaches that point, if locomotive L has not passed out of section 1 in the meantime. When locomotive L' passes point a², the armature-levers A' and A² are tilted to the left and right, respectively, setting A² at "safety" and A' at "danger."

It is the function of the batteries B' B', Fig. 1, to operate the alarm in the cab exclusively, and that of the batteries B to operate the signal-switch magnets. Of course it is to be understood that the locomotive and tender are insulated from each other, and that the only electrical connection between the truck-wheels and the rear drive-wheels is through the conductor w³ w³.

In Fig. 2 we have shown the system of blocking-signals operated from a single line of rails. In this figure the engine on section 1 has passed out of that section, so that the armature-lever A of magnet M is at "safety," while armatures A' and A² are in the reverse positions, the engines L' and L² not having yet passed out of their respective sections 2 and 3.

When engine L passes over the space a', no circuit will be made from local battery B² through the magnet M³ on the cab, and hence no alarm will be sounded, showing "safety" on section 1. As the armature A' is in reverse position, it will be seen that the local circuit from battery B² will be closed through this armature-lever by spring s' and wire w', locomotive-wheel, wire w³, magnet M³, wire w³, tender-wheel, and wire w', thus sounding an alarm, as shown. Similarly the next succeeding engine (not shown) would receive an alarm on entering section 3. As engine L' passes out of section 2 into section 1, it closes the circuit of battery B through drive-wheel,

wires w w, lower half of magnet M, and upper half of magnet M', thus reversing the switches or armature-levers A and A' and placing them to indicate "safety" to an incoming train to section 2 and "danger" for section 1. Similarly engine L² will set switch-armature A² to "safety" and A' to "danger" as it passes out of section 3 and into section 2.

The operation of the switch and draw-bridge circuits, Fig. 3, will be understood in view of what has already been said concerning the blocking-circuits, it being understood that the alarm-circuit is closed through the cab, as before, at the point a⁶. When it is desired to stop the train at a way-station, the station-master closes the circuit of the hand-switch H, Fig. 4, and the alarm is sounded in the cab, as before, the approach of the train having first been announced by the action of the lower half of the magnet M⁴ on the armature-lever A⁴, causing it to tilt to the right and close the local circuit of battery B², thereby ringing bell D. As the train arrives at the station, the circuit of battery B⁴ is closed through the upper half of magnet M⁴ at the point a⁹, thereby causing the armature-lever A to tilt into the position shown, so that the bell stops ringing.

Having thus described our invention, what we claim, and desire to secure by Letters Patent of the United States, is—

1. In a system of block-signals for railways, the combination of a main battery located at one end of a block-section in a circuit including one coil of a switching-magnet at the home station and one coil of an additional switching-magnet at a distant station, with a local battery, also located at the home station, having circuit-connections, as described, with the armature-lever of the switching-magnet, and a local circuit extending into the cab of the engine, including a magnet the armature of which controls an alarm, substantially as described.

2. In a system of block-signals for railways, the combination of a series of batteries, one for each block-section, each of which includes in its circuit one coil of a switching-magnet at the home station and an additional coil of a switching-magnet at the next station in the rear, with a local battery at each station, and circuit-connections, as described, for closing a circuit through an alarm apparatus in the cab of the engine, substantially as described.

3. In a system of block-signals, the combination of the following elements: a main or switching battery and a magnet at each block having two independent coils, switching-circuits running to the adjoining advance and rear blocks and including the separate coils of said magnets, and a local battery at each block including in its circuit the armature of the switching-magnet, the insulated ends of two adjoining rails, and an alarm-circuit on the cab.

4. In a system of block-signals for railways, the combination of the following elements:

one main or switching battery for each block included in a circuit running to one coil of each of two switching-magnets, one of said magnets being near the battery and the other at the next block to the rear, a local battery

5 at each block including in its circuit the armature of the switching-magnet, a circuit running to the insulated ends of two adjoining rails, and a signaling-magnet located on the 10 engine and included in a local circuit, substantially as described.

5. In a system of block-signals, the combination of two batteries located at each block, one of which includes circuits and switching- 15 magnets located at the home and rear ends of the block for manipulating the circuit relations of an alarm located on the engine, while the second includes in its circuit the armature of the switching-magnet, the adjoining ends of two insulated rails of the 20 track, and an alarm-magnet located on the engine and included in a local circuit, substantially as described.

6. In a system of block-signals for railways, 25 the combination of two circuits for each block connected to a single line of insulated rails, one of said circuits including a battery and one portion of the coils of two switching-magnets located at each end of the block, while 30 the other includes a second battery, the arma-

ture-lever of the first-named magnet, the adjoining ends of two insulated rails, and an alarm-magnet located on the engine and included in a local circuit, substantially as described.

35

7. In a system of block-signals for railways, the combination of the following elements: a single line of rails separated into block-sections by insulation, a single battery for each section including in its circuit the insulated 40 ends of the rails and one coil of a magnet at the battery end of the block and one coil of an additional magnet at the distant end of the block, a tilting armature-lever for each magnet adapted to tilt to the right or left, 45 according to which half of the magnet is energized, a local circuit including each tilting armature-lever and a separate battery with circuit-connections, as described, running to the insulated ends of two adjoining rails, 50 and a circuit on the engine including an alarm-magnet, whereby the engineer is warned in the event of danger in advance, substantially as described.
